US0D1019606S

(12) **United States Design Patent** (10) **Patent No.:** **US D1,019,606 S**
(45) **Date of Patent:** **** Mar. 26, 2024**

(54) **SPEAKER**

(71) Applicant: **Tempus AI, Inc.**, Chicago, IL (US)

(72) Inventors: **Brianna Gonzalez**, Chicago, IL (US);
Scot Herbst, Santa Cruz, CA (US);
Elisabeth Morris, Santa Cruz, CA (US); **William Hunter**, Denver, CO (US)

(73) Assignee: **Tempus AI, Inc.**, Chicago, IL (US)

(**) Term: **15 Years**

(21) Appl. No.: **29/820,250**

(22) Filed: **Dec. 21, 2021**

Related U.S. Application Data

(60) Division of application No. 29/758,927, filed on Nov. 19, 2020, now Pat. No. Des. 941,264, which is a continuation of application No. 29/728,691, filed on Mar. 20, 2020, now Pat. No. Des. 905,662, which is a continuation-in-part of application No. 29/693,538, filed on Jun. 3, 2019, now Pat. No. Des. 897,991.

(57) **CLAIM**

The ornamental design for a speaker, as shown and described.

DESCRIPTION

FIG. 1 is an isometric view of a bottom, front, and left side of an ornamental design for a speaker;

FIG. 2 is a front elevational view of the speaker of FIG. 1;
FIG. 3 is a rear elevational view of the speaker of FIG. 1;
FIG. 4 is a left side elevational view of the speaker of FIG. 1;

FIG. 5 is a right side elevational view of the speaker of FIG. 1;

FIG. 6 is a top plan view of the speaker of FIG. 1; and,
FIG. 7 is a bottom plan view of the speaker of FIG. 1.
The dash-dash-dash lines are included for the purpose of
illustrating portions that form no part of the claimed design.
The dash-dot-dash lines are included for the purpose of
illustrating boundary lines and form no part of the claimed
design.

1 Claim, 7 Drawing Sheets
